UNITED STATES PATENT OFFICE

113,014

DESIGN FOR A HORN OPERATING DEVICE

FOR AN AUTOMOBILE STEERING WHEEL

George E. Peters and Linus E. Russell,
Springfield, Ohio

Application January 6, 1938, Serial No. 74,117

Term of patent 3½ years

To all whom it may concern.

Be it known that we, George E. Peters and Linus E. Russell, each a citizen of the United States, residing at Springfield, Clark County, Ohio, have invented a new, original, and ornamental Design for Horn Operating Device for an Automobile Steering Wheel, of which the following is a specification, reference being had to the accompanying drawing, forming a part thereof.

In the drawing, Fig. 1 is a perspective view of a horn operating device for an automobile steering wheel, showing our new design.

Fig. 2 is a top plan view thereof.

Fig. 3 is a side elevation.

The steering wheel shown by dotted lines is of conventional shape.

We claim:

The ornamental design for a horn operating device for an automobile steering wheel, substantially as shown.

GEORGE E. PETERS.
LINUS E. RUSSELL.
